UNITED STATES PATENT OFFICE

VACLAV OCENASEK, OF NEW YORK, N. Y., ASSIGNEE, BY MESNE ASSIGNMENTS, TO
JOSEPH F. C. LUHAN, OF NEW YORK, N. Y.

FIRE GRATE

Application filed February 14, 1925. Serial No. 9,164. Renewed November 5, 1929.

My invention relates to improvements in fire grates on which a fire may be advantageously maintained for any purpose, but which is peculiarly adapted for use in a steam or hot water boiler. The general object of my invention is to produce a fire grate which is unusually strong in proportion to its weight, which has an abnormally large air delivery from beneath, which has a plain top surface which can be advantageously water cooled and adapted to have the heated water serve as a feed water heater for the boiler if desired, and which by reason of its general construction and particularly of its means for distributing a large quantity of air uniformly to the fire, is adapted to burn any fuel to advantage, and particularly adapted to burn cheap and finely divided fuels which could not be burned to so good advantage on other grates.

In consonance with the idea above expressed, I provide a grate section which can be used in multiple to make a grate of any desired surface, and which has longitudinal strengthening ribs on the under side deepened towards the center to give the best bracing effect, and has also transverse ribs and holes through the top surface preferably funnel shaped. By reason of the foregoing construction the grate is made comparatively light, and the ribs are disposed so as to form a series of chambers on the under side of the grate section, from the upper parts of which chambers the sheet-like openings extend through the top wall of the grate with the result that the air or steam used to promote combustion will flow through the several chambers, be prevented by the walls thereof from eddying and forming unequal distribution of air, and the inflowing air and steam, or both, will thus be distributed uniformly to all parts of the grate section, and will flow upwardly in a multitude of jets tending to keep the grate surface clean, and delivering an ample supply of air or oxygen to the fire surface, thus promoting as nearly as possible complete combustion. The arrangement noted is equally adapted for either natural or forced draft and for various kinds of fuel. Through

the main ribs and the headers which support them I can if desired direct a flow of water which will absorb the heat from the grate thus keeping it cool, and which can be used to feed the boiler or for other purposes. The grate is preferably placed at an inclination when used, so that the combustible part of the fuel will gravitate to the lower end of the grate, where it can be dumped by means of a special clinker grate which I arrange for this purpose, and by constructing the grate with a series of chambers and jet openings as described, arranging an air chamber below the grate, and by the use of suitably disposed baffles in the air chamber I control the inflowing air or steam or mixture thereof to such advantage that practically no ashes fall through the grate itself, but they are delivered to the clinker grate above noted, and the small accumulation of matter in the air chambers can be easily blown out as hereinafter described. It will be further noted that by the arrangement of ribs forming the air chambers on the under side of the grate, I not only acquire great uniformity of air delivery, but the grate is strengthened to such an extent that it is unlikely to become warped or distorted. The above advantages and others will appear more clearly from the description which follows.

Reference is to be had to the accompanying drawings forming a part of this specification, in which similar reference characters indicate corresponding parts in all the views.

Figure 1 is a plan view of the grate embodying my invention.

Figure 2 is a longitudinal section thereof.

Figure 3 is an end view of the grate and its casing.

Figure 4 is a cross section through the grate and casing.

Figure 5 is a plan view of one of the grate sections.

Figure 6 is a longitudinal section of the structure shown in Figure 5.

Figure 7 is a broken plan view of the inner header which can be used as a part of the grate when the latter is water cooled.

Figure 8 is a broken elevation of the header shown in Figure 7.

Figure 9 is a cross section through the grate section shown in Figure 5.

5 Figure 10 is a plan view of a slightly modified form of a grate section.

Figure 11 is a side elevation of the grate section shown in Figure 10.

Figure 12 is a cross section on the line 10 12—12 of Figure 10, and

Figure 13 is a broken detail section on the line 13 of Figure 10.

As illustrated in Figure 1 the grate is formed of a series of sections 10, 10^a and 15 10^b, and as many of these sections can be used as is desirable. The grate is supported on suitable outer and inner frames 9 and 11 which may be of any suitable kind, and where the grate is to be water cooled it is 20 provided with headers 12 and 13 which are supported on ledges 14 and 15 of the frames 9 and 11, but which may obviously be supported in any convenient way.

Each grate section is preferably rectangular in shape, flat on the top, and provided with a central longitudinal rib 17 with depending side ribs 18 and with longitudinal ribs 19 disposed between the ribs 17 and 18, and these ribs 19 are preferably 30 deepened towards the center so as to give them a truss effect and thus greatly stiffening the grate section. The grate section is also provided with transverse ribs 20 which are obliquely arranged as shown clearly in 35 Figure 5 so as to form a series of diamond or semi-diamond chambers, and the ribs 20 can be otherwise arranged if desired to form the air chambers beneath the grate and to give the necessary strength, but the 40 straight lines diagonally arranged are preferable because of ease of construction. If desired the central rib 17 may be made thinner and deeper as shown at 16^a in Figures 10 to 12, when a grate section 10^a is to be formed and is without the water cooled 45 feature. The ribs 19^a in such case may be thickened and deepened, and the diagonal ribs 20^a may be given increased depth as shown clearly in Figure 13 so as to give additional strength to the grate.

The top surface of the grate is pierced by numerous holes 21, which as shown in Figures 4, 9 and 12 preferably taper from the bottom to the top, thus making them funnel shape so that the up-flowing air to promote combustion will issue through the grate in the form of a multitude of jets, thus serving to keep the grate surface clean, and forcing the oxygen of combustion to the 55 top of the fire. In the drawings I have shown these holes 21 in only a part of the figures, but it will be understood that the whole surface is pierced as illustrated at the 60 top hand in Figures 5 and 10.

65 In connection with the grate I have shown

a water pipe 22 for supplying feed water to the boiler heated by the fire on the grate, and in Figure 3 I have shown diagrammatically the direction of the water flow. The pipe 22 has a valve 23 and a branch 70 pipe 24 controlled by valves 25 and 25^a arranged at opposite sides of the grate. The water diverted through the line 24 is made to flow through the grate, and can be regulated so that just sufficient water will pass 75 through to supply heated feed water to the boiler.

As a convenient arrangement for the passage of water through the grate I have shown a pipe line 24 having sections 26 and 26^a 80 delivering into the headers 13 and 12, and the header 12 has an elbow bore 29 in one part thereof, while a similar elbow 30 is held in a part of the header 13, these registering with the bores 28—28^a—28^b of 85 the grate sections 10—10^a—10^b. The ends of the elbow bores 29 or 30 register with the bores 28—28^a and 28^b, which extend longitudinally through the ribs 17 of the grate sections, and the bores 28 and 28^b also register with the sections 26 and 26^a of the headers. It will be understood, of course that there may be a greater or less number of elbow bores in the headers, depending on the 90 number of sections of the grate, and these bores by which the water flow is led through the several central ribs of the grate sections may be produced in any convenient way. I have found that a good way is to have steel 95 pipes cast in the headers and in the grate ribs, and at the points where the header bores and grate bores meet suitable high pressure joints are used to prevent leakage, and any joints suitable for the purpose can 100 be used.

105 The headers 12 and 13 can be held in place by suitable means such as bolts or the like and if uncooled grate sections 10^a are used, it will be obvious that the headers 13 and the piping connections will not be employed.

Beneath the grate is a casing 32 forming 110 an air chamber, and this can be held on the ledges 33 on the frames 9 and 11 or can be otherwise supported. The air chambers thus formed should have an air inlet 34 through the frame 9 at the front end thereof, and a suitable door can be provided for this opening. I also preferably arrange at intervals swinging baffles 35 which prevent eddying currents from being set up in the air chambers, and this arrangement in connection with the separate chambers on the under side of the grate sections, causes a very even 115 flow of air to every part of the grate.

The grate is arranged at an inclination 120 from front to back as shown clearly in Figure 2, and can be used at normal draft, or air or steam or both may be injected into the chamber beneath the grate through the opening 34.

At the lower part of the casing 32 is an opening 36 closed by the free edge 37 of a swinging pan which has an opening 38 therethrough and which is arranged beneath the opening 36 above referred to. The axle 39 of the pan is hung on suitable supports 39^a and provided with a weighted arm 40 which keeps the part 37 of the pan normally in position to close the opening 36. The arm 40 is provided with a pull rod 42 extending 10 to the front of the furnace, and the rod should have a handle 43 or the like to facilitate its easy operation. When desired the rod 42 can be pulled, thus swinging the member 37 from beneath the opening 36, 15 and any accumulation of soot or dust in the casing 32 can be blown out, and as it drops from the opening 36, will also pass through the opening 38 in the member 37.

Opposite the inner and lower end of the 20 grate I place a clinker grate 44, and the unconsumed ash and refuse from the fuel will collect on this grate which can be dumped when desired. To this end the grate 44 is provided with an axle 45 mounted in suitable supports 46, and the axle has a crank 47 provided with a pull rod 48 extending to the front of the furnace and provided with a handle 49. Thus by pulling the rod the 25 grate 44 can be dumped.

30 From the foregoing description it will be seen that I have provided a very simple, strong and efficient grate adapted to consume fuel of practically any kind to the best advantage, and furthermore a structure 35 which is cheap, not liable to distortion, and which can be used to great advantage as a feed water heater whereby the double purpose is conserved of keeping the grate cool and heating the water.

40 Attention is called to the fact that the bores of the grate and connected header are preferably made by casting the grate or header around the pipe. This is particularly advantageous where it is desired to use 45 water of high pressure. Often pressures are used so high that ordinary cast iron would not withstand them, but by using high pressure pipe in the bores, the pressure is easily withstood, and moreover the action of the 50 external heat and internal high pressure water is such that the castings become gradually toughened and annealed.

I claim:

1. A fire grate comprising a plate providing a plain top surface and having a plurality of openings extending therethrough, longitudinal strengthening ribs on the under side of said plate and diagonally arranged ribs connecting the longitudinal ribs, said 55 diagonal ribs crossing one another to form a plurality of substantially diamond-shaped air chambers.

2. A fire grate comprising a plate providing a plain top surface and having a plurality of openings extending therethrough,

longitudinal strengthening ribs on the under side of the plate and high pressure resisting pipes in certain of said ribs, adapted to convey a cooling medium therethrough and diagonally arranged ribs on the under side of said plate crossing one another to form a plurality of substantially diamond shaped air chambers. 70

In testimony whereof, I have signed my name to this specification this 16th day of January, 1925. 75

VACLAV OCENASEK.
